[57] CLAIM

The ornamental design for a camera with flip-up flash,
as shown and described.

DESCRIPTION

FIG. 1 is a front elevation view of a camera with a
flip-up flash according to my new design, showing the
flash folded down;

FIG. 2 is a rear elevation view thereof;

FIG. 3 is a top plan view thereof;

FIG. 4 is a bottom plan view thereof;

FIG. 5 is a right-side elevation view thereof;

FIG. 6 is a left-side elevation view thereof;

FIG. 7 is a front elevation view of the camera, showing
the flash flipped up;

FIG. 8 is a rear elevation view thereof;

FIG. 9 is a top plan view thereof;

FIG. 10 is a bottom plan view thereof;

FIG. 11 is a right-side elevation view thereof;

FIG. 12 is a left-side elevation view thereof;

FIG. 13 is a top, front perspective view thereof; and,

FIG. 14 is a bottom rear perspective view thereof.
